[57] CLAIM

The ornamental design for a pair of golf shoes, as shown and described.

DESCRIPTION

FIG. 1 is a bottom, left and rear perspective view of the right side of a pair of golf shoes, showing our new design;
FIG. 2 is a top, right and front perspective view thereof; and,
FIG. 3 is a bottom view thereof.

The left side of the pair of golf shoes is a mirror image of the right side shown.
